TROLLEY WIRE HANGER

Samuel S. Matthes, Mansfield, Ohio, assignor to
The Ohio Brass Company, Mansfield, Ohio, a
corporation of New Jersey

Application August 10, 1933, Serial No. 684,539

12 Claims. (Cl. 173—28)

My invention relates to supports for conductors and has particular reference to supporting trolley conductors.

One of the objects of my invention is to provide a hanger in which the parts are relatively adjustable in order that the hanger may be applied to span wires which are obliquely disposed to the horizontal or may be applied to other supports the axes of which are obliquely disposed to the vertical and in all cases the trolley wire and its ear or clamp may be positioned normal.

Other objects will be disclosed as I further describe my invention.

My invention resides in the new and novel construction, combination and relation of the various parts hereinafter described and as shown in the accompanying drawing:—

In the drawing:—

Fig. 1 is a side view in elevation and partial section of my invention.

Fig. 2 is a side view of my hanger as taken at 90° from that of Fig. 1.

Fig. 3 is a top view of my hanger.

Fig. 4 is the top view of the suspension yoke.

Fig. 5 is a top view of the suspending stud.

Fig. 6 is a side view of the top portion of the hanger body showing the socket formation.

Fig. 7 is a sectional view on the line 7—7 of Fig. 3.

In the preferred embodiment of my invention I employ a hanger body 1 provided with a downwardly projecting flange to form an inverted cup-shaped receptacle and positioned within the receptacle is a second flange 2 also forming an inverted cup-shaped receptacle in which is mounted the supporting stud 3 having a conically-shaped head 4 and projecting threaded portion 5. The lower edge of the flange 2 is turned inwardly to provide an annular flange 6 to better aid in the support of the stud 4.

The receptacle formed by the downwardly projecting flange of the body 1 and the flange 2 are each filled with insulating composition 7 which is molded in position under pressure and maintains the body 1 and the stud 3 in separated insulated relation.

The body 1 is provided with a dome-shaped portion 8 which has an inverted T-shaped side opening 9 opening into a receptacle 10 and also having a top opening 11. The side opening 9 is of less extent than the receptacle 10 and the inner upper surface 12 of the receptacle 10 is curved to provide a bearing for the suspension stud 13.

The stud 13 is provided with a head portion 14 and a threaded shank 15. The head 10 has a

curved surface 16 corresponding to the curvature of the surface 12. The stud 13 projects through the slot 11 which is sufficiently large to permit of limited universal movement of the stud 13 relative to the body 1 during which movement the curved surfaces 12 and 16 move in contact and relative to each other. The outer surface 17 of the dome 8 is curved and has a center of curvature common with that of the inner surface 12 of the dome.

Mounted upon the exterior of the dome 8 is a suspension yoke 18 having projecting arms 19 and the ends thereof formed with slots 20 to receive the cross span wire shown in dotted lines by which the device is supported. In Fig. 1 the axis AA of the span wire is shown horizontal which is the usual position which the span wire takes but there are occasions when the axis of the span wire at the point of supporting the hanger is obliquely disposed as shown by the line BB in Fig. 1 and in that case it is necessary to have the yoke member positioned with respect to the body 1 of the hanger such that it will grip the span wire and still maintain the axis CC of the stud 3 vertical.

The yoke 18 is provided with an inverted cup-shaped recess 21 having a spherical surface 22 corresponding to the surface 17 on the dome with which it contacts.

An opening 23 in the yoke connects with the recess 21 and has two flat surfaces 24 which are engaged by the flattened surfaces 25 on the stud 13 which extends through the opening 23 and prevents relative rotation of the yoke and stud. The yoke and stud will have limited universal movement relative to the body. Mounted upon the end 15 of the stud 13 is a nut 26 and a spring lock washer 27 by means of which the yoke and body may be held in any adjusted position desired or the tension between the yoke and dome may be so adjusted that the yoke and body will move under stress thus constantly adjusting themselves to conditions.

The yoke is provided with a groove 28 to receive the span wire and thus the span wire is in engagement only with the yoke and does not contact with the body of the hanger.

Integrally formed with the body 1 is a projecting lug 29 which is engaged at times by the lug 30 integrally formed with the yoke 18. These lugs form convenient means for applying the body 1 to the conductor clamp or ear secured to the lower end of the stud 13 before the hanger is positioned upon the span wire.

In installing the hanger the nut 26 is loosened sufficiently to permit the yoke and body to be

rotated relative to each other and the end 5 of the stud 3 is then brought into cooperative relation with the trolley wire ear or support and the yoke 18 is then rotated in a clockwise direction 5 (see arrow, Fig. 3) until the lug 30 engages the lug 29 and continued rotation of the yoke 18 will rotate the body 1 and secure the stud 3 to the supporting ear or clamp. When this operation has been completed the yoke 18 is then rotated 10 so as to be applied to the span wire and this having been done the nut 26 may be tightened to hold the parts in a fixed relation or the nut may be tightened sufficiently only to permit the parts to move under stress sufficient to overcome the friction 15 between the yoke 18 and the dome 8.

If it is desired to replace the trolley wire clamp or ear with a new one then the yoke is disengaged from the span wire and rotated in a counter-clockwise direction until the lug 30 engages the 20 lug 29 on the opposite side to that shown in Fig. 3 and continued rotation will then disengage the stud 3 from the clamp or ear.

Modifications may be made to the disclosure herein shown and described as, for instance, the 25 device may be made to attach to other forms of supports than a span wire and still have the axis of the support adjustable relative to the axis CC of the stud 3.

Having disclosed my invention, I claim:—

30 1. A hanger for a trolley wire comprising in combination a body member forming an inverted receptacle, an upstanding wall with inturned edge within the receptacle forming a second inverted receptacle within the first, a supporting 35 stud with enlarged head at one end mounted within the second receptacle and having means at the other end to receive a trolley wire support, insulating material between the stud and walls of the receptacle to hold the body and stud 40 in fixed relation, a dome-shaped projection integral with the closed end of said body and having a recess with a curved surface and an inverted T-shaped opening through the side of the 45 said projection and an opening through the top of said projection into said recess, the outer surface of said projection being curved in conformity with the curvature of the surface of the recess, an inverted bolt having the bearing surface of the bolt head curved to conform to that of the 50 recess surface positioned in said dome recess, a yoke shaped member movably mounted on the dome and held in assembled position by a nut on the bolt, means on the yoke to receive a supporting span wire and means on the yoke to engage 55 means on the body to limit the relative rotation of the yoke and body and to cause the two to rotate in unison, the nut on the bolt being adjustable to permit either relative movement of the yoke and body or hold the parts against relative movement at will.

60 2. A trolley wire hanger comprising an insulated body forming a recess and a stud mounted in the recess and held in position by a mass of interposed insulating material, means on the stud to secure a wire support thereto, a dome shaped member projecting from the body and having a recess therein to receive a headed stud and an inverted T-shaped opening communicating with said recess through which the stud may be passed, the outer surface of the dome member 65 and the inner surface of the recess being spherical and having a common center of curvature, a yoke member having a recess with a surface conforming to that of the dome mounted thereon 70 and having universal movement therewith, an 75

opening through the yoke and communicating with the recess in the yoke, a headed and threaded stud associated with the dome and the yoke members and the head having a surface conforming to and engaging the surface of the dome recess and having universal movement relative to the dome and locked with the yoke to move in unison therewith and means on the threaded portion of the last mentioned stud to hold the yoke and stud in assembled relation with the dome and means on the yoke member to receive a support for the hanger.

80 3. A trolley hanger comprising an inverted cup-shaped body member and a supporting stud mounted therein and having an exposed portion to be secured to a wire support and insulation interposed between the body and stud to hold the parts in fixed and insulated relation, a recessed dome shaped member projecting from the body member, suspending means mounted on the exterior of the dome shaped member to suspend the body from an overhead support and having universal movement relative to the body and means to secure the suspending means to the overhead support and means mounted in said recess and projecting therefrom to hold the suspending means and body in assembled and fixed relation and permit said universal movement at will.

90 4. A trolley hanger comprising an inverted cup-shaped body member and a supporting stud mounted therein and having an exposed portion to be secured to a wire support and insulation interposed between the body and stud to hold the parts in fixed and insulated relation, a recessed dome shaped member projecting from the body member, suspending means mounted on the exterior of the dome shaped member to suspend the body from an overhead support and having universal movement relative to the dome shaped 100 member and means to secure the suspending means to the support and separately formed means positioned partly within the dome recess to hold the suspending means and dome shaped member in assembled and fixed relation and permit said universal movement at will.

105 5. A trolley wire hanger comprising a body having an inverted cup-shaped member provided with a convex exterior spherical surface, a supporting stud mounted within the body member and interposed insulation holding the body member and stud in fixed and insulated relation, means on the stud to secure it to a trolley wire ear, a recessed dome-like member projecting from the cup shaped member and having a 110 spherical convex exterior surface, a support member mounted on the exterior surface of the dome-like member and having a concave spherical surface conforming to the said convex surface on the dome-like member and means to secure the 115 support member to an overhead support and means mounted in the recess of the dome-like member to secure the support and body members in assembled relation and to hold them in either fixed relation or a universally movable relation at will.

120 6. A trolley wire hanger comprising an inverted cup-shaped body member having a convex exterior spherical surface, a supporting stud mounted within the body member and interposed insulation holding the body member and stud in fixed and insulated relation, means on the stud to secure it to a trolley wire ear, a support member mounted on the exterior surface of the 125 body member and having a concave spherical 130 surface conforming to the said convex surface on the dome-like member and means to secure the support member to an overhead support and means mounted in the recess of the dome-like member to secure the support and body members in assembled relation and to hold them in either 135 fixed relation or a universally movable relation at will.

140 7. A trolley wire hanger comprising an inverted cup-shaped body member having a convex exterior spherical surface, a supporting stud mounted within the body member and interposed insulation holding the body member and stud in fixed and insulated relation, means on the stud to secure it to a trolley wire ear, a support member mounted on the exterior surface of the body member and having a concave spherical 145 surface conforming to the said convex surface on the dome-like member and means to secure the support member to an overhead support and means mounted in the recess of the dome-like member to secure the support and body members in assembled relation and to hold them in either fixed relation or a universally movable relation at will.

- surface conforming to the said convex surface and means to secure the support member to an overhead support and elongated means rotatable simultaneously about its longitudinal axis with the rotation of the support member to secure the support and body members in assembled relation and to hold them in either fixed relation or a universally movable relation at will. 80
7. A trolley wire hanger comprising a body member and a supporting member for a trolley wire holder in fixed and insulated relation, the body having a recessed integrally formed dome-like part with an opening communicating with the recess to receive a headed suspending stud, the outer surface of the dome and the inner surface of the recess provided with spherical surfaces, a suspending member mounted on the dome part to rotate relative thereto about the axis of the supporting member or in a plane obliquely disposed to the said axis, a suspending stud mounted in the recess and securing means on said stud and coacting with the suspending member to hold the member in assembled relation to the body. 85
- 10 8. A trolley wire hanger comprising a recessed body member having a recessed dome-like part integrally formed therewith and an opening into the recess in the domed part through which a headed stud may be passed into the recess, a headed stud in said recess, a suspending member mounted on the body to either rotate or pivot relative thereto or both, means on the stud to hold the suspending member in any adjusted position relative to the body at will and a supporting stud mounted in insulated relation to the body and having means to secure thereto a trolley wire holder. 90
- 15 9. A trolley wire hanger comprising a recessed body member having an integrally formed recessed dome-like part and an inverted T-shaped opening into the recess of the domed part, a headed and threaded stud mounted in the dome recess and projecting therefrom and a suspending member secured to the headed stud and in engagement with the outer surface of the dome-like part to move in unison with the stud and having means to secure the suspending member to an overhead support, means on the stud to hold the suspension member and the body in engagement and in a predetermined relation and means held in fixed and insulated relation to the body to support a trolley wire holder. 95
- 20 10. A trolley wire hanger comprising a recessed body having a dome-like surface, suspending means mounted on the dome-like surface and having means to secure the suspending means to an overhead support, the suspending means having universal movement relative to the body and elongated adjustable means to secure the suspension means and the body in assembled relation, 100
- 25 the suspension means and the adjustable means interlocked to move in unison whenever the suspension means moves relative to the body and elongated means mounted in the body recess in insulated relation thereto to support a trolley wire holding member, the suspension means and the body being relatively adjustable such that the axes of the two elongated means may be either aligned or obliquely disposed at will. 105
- 30 11. A trolley wire hanger comprising a body member having two recesses separated by a partition forming part of the body, a stud mounted in one recess and having an exposed portion to be secured to a conductor support and insulation interposed between the stud and body to hold the parts in fixed and insulated relation, the body having side and end openings communicating with the other recess, a supporting member mounted in the said other recess and projecting therefrom and having a head portion positioned within the recess and an elongated transverse portion having grooved ends and a grooved central portion to receive and grip a span wire, the headed portion of the supporting member having a convex surface engaging a concave surface of the said other recess, the supporting member and the body member being rotatable relative to each other and also relatively movable such that their axes may be either in alinement or obliquely disposed to each other at will and means to prevent the said relative rotation and hold the supporting member and body with their axes in a predetermined relation. 110
- 35 12. A trolley wire hanger comprising a body member having two recesses separated by a partition forming part of the body, a stud mounted in one recess and having an exposed portion to be secured to a conductor support and insulation interposed between the stud and body to hold the parts in fixed and insulated relation, the body having side and end openings communicating with the other recess, a supporting member mounted in the said other recess and projecting therefrom and have a head portion positioned within the recess and an elongated transverse portion having grooved ends and a grooved central portion to receive and grip a span wire, the headed portion of the supporting member having a convex bearing surface engaging a concave bearing surface of the said other recess, the supporting member and the body member being rotatable relative to each other and also relatively movable such that their axes may be either in alinement or obliquely disposed to each other at will and means to force said convex and concave bearing surfaces into engagement and prevent relative movement of the supporting member and the body member. 115
- 40 13. A trolley wire hanger comprising a body member having a dome-like surface, suspending means mounted on the dome-like surface and having means to secure the suspending means to an overhead support, the suspending means having universal movement relative to the body and elongated adjustable means to secure the suspension means and the body in assembled relation, 120
- 45 14. A trolley wire hanger comprising a body member having a dome-like surface, suspending means mounted on the dome-like surface and having means to secure the suspending means to an overhead support, the suspending means having universal movement relative to the body and elongated adjustable means to secure the suspension means and the body in assembled relation, 125
- 50 15. A trolley wire hanger comprising a body member having a dome-like surface, suspending means mounted on the dome-like surface and having means to secure the suspending means to an overhead support, the suspending means having universal movement relative to the body and elongated adjustable means to secure the suspension means and the body in assembled relation, 130
